O. D. LUCAS

BREECH-LOADING GUN

Filed March 3, 1923

UNITED STATES PATENT OFFICE.

OWEN DAVID LUCAS, OF BAYSWATER, LONDON, ENGLAND, ASSIGNOR TO VICKERS LIMITED, OF LONDON, ENGLAND, A BRITISH COMPANY.

BREECH LOADING GUN.

Application filed March 3, 1923. Serial No. 622,516.

To all whom it may concern:

Be it known that I, OWEN DAVID LUCAS, a subject of the King of Great Britain, residing at 49, Linden Gardens, Bayswater, in the county of London, England, have invented certain new and useful Improvements in or Relating to Breech Loading Guns, of which the following is a specification.

10 This invention relates to breech loading guns of the kind intended for projecting signal shells into the air for signalling to aircraft from aerodromes or ships, these guns being usually non-recoiling and smooth bored.

According to the present invention the breech screw is rotatably mounted in a carrier or cradle which is slidably carried by strut or stay members forming part of the 20 mounting for the gun tube or barrel, the said carrier being moved along these members away from the breech end of the tube for loading. The said carrier is preferably made in two parts or halves held together, 25 with the breech screw between them, by engagement with the said strut members. These carrier parts may have lateral projections provided with recesses conforming to the shape of the strut members, these recesses being of curved formation when, as is preferred, the said members are of circular cross-section. On one side the lower wall of the recess in each part of the carrier is cut away and the corresponding 30 strut member is also cut away at a point near its rear or lower end so that when the carrier has been moved into the appropriate position the upper part of the carrier can be lifted out to permit the breech screw to be removed, after which the other part of the carrier can also be lifted out.

In order that the said invention may be clearly understood and readily carried into effect, the same will now be described more fully with reference to the accompanying drawings, in which:—

Figures 1 and 2 are respectively a side elevation and a rear elevation showing a

gun constructed in accordance with the invention, 50

Figure 3 is an axial section of the breech screw,

Figures 4 and 5 are end elevations of the upper and lower halves of the aforesaid 55 breech screw carrier, and

Figure 6 is an axial section of the right-hand strut member.

A, A are the aforesaid strut members forming part of the mounting for the gun tube or barrel B. These strut members are carried by a ring B¹ connected to the barrel which ring has a lug b¹ trunnioned to a pillar C carried by a base member C¹ having an arc C² to which a cross member A¹ carried by the lower ends of the said strut members can be clamped by a clamping handle C³ to hold the gun tube at the desired angle of elevation. The mounting shewn is of the naval type and is attached by clips to the bridge of the vessel or to stanchions. If the mounting is required to be self-supporting, the ring B may have two additional lugs to which are attached two additional strut members socketing their lower ends into an extension of the base member C¹. D is the breech screw which, in the example shown, is in the form of a cup having internal interrupted threads or collars for engaging with external interrupted threads or collars on the rear end of the gun tube or barrel B. E, E¹ are the upper and lower halves of the breech screw carrier in which the breech screw is rotatably mounted, the said breech screw having a circumferential recess (as shown in Figure 3) in which parts of the said halves of the breech screw carrier are disposed. The upper carrier half E has lugs or lateral projections e, e (one on each side) having curved recesses for engaging with the strut members A, A which are of circular cross-section. The lower wall of the right hand recess is cut away as shown in Figure 4 to still leave a portion of the curved recess below the centre line of the recess so that the said carrier half cannot be raised so long as the right hand recess engages with the

80

95

circular-section strut member. The lower carrier half has two pairs of spaced lugs or lateral projections e^1, e^1 , the aforesaid lugs or projections e, e fitting between each pair 5 of the lugs or projections e^1, e^1 as shown in Figures 1 and 2. The right hand pair is cut away at the lower part as above described and as shown in Figure 5. It will therefore be seen that the two halves of the 10 carrier are normally held together (with the breech screw rotatably carried thereby) by the engagement of these recesses with the strut members A, A. At its lower part the right hand strut member is cut away at a 15 (Figure 2) on its inner surface sufficiently to enable the carrier halves to be lifted without impediment when the carrier has been moved rearwards into a position to bring the right hand lugs or lateral projections 20 on the carrier halves opposite the said cut away part of the strut member. The upper carrier half is first lifted with the left hand strut serving as a pivot and is then removed. The lower carrier half is then 25 similarly lifted and removed with the breech screw in position and the latter can then be removed from the lower carrier half after a firing mechanism casing E² (which is connected by detachable pins e^2, e^2 , Figure 2, to inwardly projecting lugs e^3, e^3 , Figure 5, on the lower carrier half) has been 30 removed. This casing is situated between the strut members A, A and does not offer any impediment to the removal of the said 35 lower carrier half. The firing mechanism is preferably constructed in accordance with the specification of my copending application, Serial No. 622,765 filed March 5, 1923. The breech screw carrier has a handle E^x 40 (forming part of the lower carrier half) for moving the carrier and the parts carried thereby along the strut members A, A and the breech screw has on its rear part a two-handled lever D^x by which the breech screw 45 can be angularly displaced for locking it to and unlocking it from the gun barrel. The said breech screw is held in its unlocking position during the movements of the carrier on the aforesaid strut members by a 50 cartridge extractor E³ (Figure 1) which is pivoted to the lower carrier half and which engages with a notch in the breech screw. The nose of this extractor engages with an inclined surface b on the rear part of the gun 55 tube as the carrier approaches the breech end of this tube and is thereby disengaged from the notch in the breech screw. In order to prevent accidental rotation of the breech screw after such disengagement has taken 60 place and before the breech screw has reached its correct position for locking, the aforesaid ring B¹ secured to the rear part of the gun tube has a rearwardly extending narrow plate B² having a nose b^2 which 65 engages with a recess d^1 in the front collar of

the breech screw until the latter occupies the correct position for rotation (with the said front collar disposed within the ring B¹) at which time the said recess lies in front of the nose b^2 and the latter does not then impede the locking movement of the breech screw. The aforesaid upper carrier half is formed with a passage E⁰ (see Figure 4) to accommodate the nose b^2 during the above 70 described operation. 75

The muzzle of the gun tube is closed when required by a cap F pivoted to a ring F¹ on the tube and means are provided whereby the gun cannot be fired unless the cap is sufficiently open to permit firing to occur 80 without danger. For this purpose the pivot pin f of the said cap has an eccentric operating upon a rod F² connected to a member which, when the cap is closed or partly open, occupies a position obstructing the firing 85 movement of part of the firing mechanism but which, when the cap is sufficiently open, occupies a position permitting firing movement of the said part to occur. The said member may for example comprise a rod 90 slidably mounted in one of the aforesaid strut members which are made tubular. This particular strut member has a hole in its inner wall for the passage of the end of the firing plunger described in the aforesaid application Serial No. 622765. The passage 95 of the plunger through this hole is prevented by the said rod when the cap F is closed or only partly open and firing is thereby prevented. 100

The gun is fired by a lanyard G passing over a swivelling pulley G¹ on the aforesaid cross member A¹ this lanyard being connected to a spring-controlled slide a (Figure 8) disposed in the right hand strut member A. This slide has a pin a¹ which projects through a slot a² in the said strut member and co-operates with a firing lever G² carried by the aforesaid firing mechanism casing E². 105 110

What I claim and desire to secure by Letters Patent of the United States is:—

1. In a breech loading gun mount, a breech screw, a carrier in which the breech screw is rotatably mounted, and inclined shock-resisting strut members comprising part of said mount on which said carrier is slidably mounted, the said carrier being movable along the strut members away from the breech end of the tube for loading. 115 120
2. In a breech loading gun, a breech screw, a carrier in which the breech screw is rotatably mounted, and strut members on which said carrier is slidably mounted, said carrier comprising two sections held together by engagement with the strut members, the breech screw being located between said sections. 125
3. In a breech loading gun, a breech screw, a carrier in which the breech screw is ro- 130

5 tatably mounted, strut members on which said carrier is slidably mounted, said carrier comprising two sections provided with lateral projections having recesses for co-operation with the strut members to hold the sections on the strut members and to render the carrier slidable thereon, the lower wall

of one recess in each carrier section being cut away and the corresponding strut member being also cut away at a point near its rear or lower end to permit removal of the carrier sections. 10

OWEN DAVID LUCAS.
